UNITED STATES PATENT OFFICE.

EDWARD A. MORROW, OF CHESTER, ARKANSAS.

CAR-COUPING DEVICE.

SPECIFICATION forming part of Letters Patent No. 449,423, dated March 31, 1891.

Application filed November 19, 1890. Serial No. 371,930. (No model.)

To all whom it may concern:

Be it known that I, EDWARD A. MORROW, a citizen of the United States, residing at Chester, in the county of Crawford and State of 5 Arkansas, have invented certain new and useful Improvements in Pin and Link Lifters; and I do hereby declare the following to be a full, clear, and exact description of the invention, such as will enable others skilled in the 10 art to which it appertains to make and use the same.

My invention consists in a new and improved pin and link lifter which is adapted to be attached to the ends of cars using the 15 common link-and-pin coupling and which will enable cars provided with the old link-and-pin coupling to be coupled and uncoupled from the sides of the cars or from their tops without going between them, thus at 20 a minimum of cost doing away with all necessity for going between the ends of the cars in coupling or uncoupling them and preventing the accidents which now daily occur.

The great advantage of my invention is 25 that it is simple and inexpensive and can be applied to all cars now using the common link-and-pin coupling without making any change in the same, while it is thoroughly effective and practical in its operation.

Referring to the accompanying drawings, Figure 1 is a perspective front view of the 30 end of a car provided with my invention. Fig. 2 is a perspective view taken from the under side of the car, and Fig. 3 is a sectional view taken on line $\alpha\alpha$ of Fig. 3.

The same numerals of reference indicate corresponding parts in all the figures.

Referring to the several parts by their designating-numerals, 1 indicates the end of a 35 car, which is shown provided with my invention, 2 indicating the draw-head, and 3 and 4 indicating, respectively, the ordinary link and pin.

My pin-raising attachment consists, first, 40 of two horizontal levers 5, which are pivoted at the points 6 on the end of the car and have their inner ends curved up and then outward, with their inner slotted extremities pivotally connected with the upper end of the coupling- 45 pin. The outer ends of these levers 5 project out beyond the sides of the car and are there rounded to form convenient handles, and it

will be seen that by means of these levers the coupling-pin can be raised and lowered and the cars coupled and uncoupled from the 55 sides of the car without the slightest necessity for going between them. When the outer ends of either of the levers 5 is pressed down to raise the coupling-pin, it can be secured in that position by engaging it in a recessed 60 catch-plate 7, these catch-plates being secured at the sides of the car ends, as shown.

To raise the pin from the top of the car, I employ a vertical lever 8, having an end ring at its upper end, and having its hooked lower 65 end extended under the inner ends of the horizontal levers 5, and it will be seen that by pulling up this lever the inner ends of the levers 5 will be raised and the coupling-pin thus drawn up, and the cars can be thus coupled 70 and uncoupled from their tops as well as from their sides. When the vertical lever 8 is raised, it can be secured in its lifted position by engaging a stop 9, formed on it on the upper side of a bail 10, through which the lever 75 passes.

The link-adjuster consists of a plate 11, which is bent up at its center at right angles and has its upper edge recessed, so that the link will rest upon it and will be held from 80 sliding off to either side, the lower horizontal part of this plate being slotted longitudinally at 12 to prevent the lower end of the coupling-pin from interfering with its movements. The plate 11 is secured to the forward end of 85 a rod 13, which passes through vertical slots 14 15, formed in the cross-pieces 16 on the bottom of the car, and the rear part of the rod passes through a bearing-roll 17, which is journaled at its ends in bearings on the bottom of the car. A spiral spring 18 encircles the forward part of the rod 13 between a fixed pin and washer 19 and the front cross-piece 16, and the spiral spring 20 encircles the rear part of the rod between the fixed pin 21 and 95 the rear side of the bearing-roll 17.

22 22 indicate curved levers, which are pivoted on the end of the car, as shown, with their slotted lower inner ends 22¹ passing around the rod 13 near its outer end.

The coupling-link rests upon the top of the plate 11 at a point beyond the center of its length, so that when the said plate is raised or lowered the outer end of the link will be

raised or lowered, and this is effected from the sides of the car by pressing down or raising the outer ends of the levers 22. It will thus be seen that the outer end of the link 5 can be easily raised from the sides of the car to suit the height of the draw-head of the approaching car, the vertical slots 14 15 in the cross-pieces 16 admitting of the vertical movement of the rod 13 and the plate 11, 10 while the roll 17 turns on its end pivots to admit of this movement.

The outer end of the link is raised or lowered from the top of the car by a vertical lever 23, which runs through staples or eyes on 15 the end of the car and has its lower curved end extending under the rod 13 near the plate 11, as shown.

The spiral spring 18 is to enable the plate 11 to slide in as the draw-heads of the meeting cars bump together, thereby preventing its being broken or mashed, while the spiral spring 20 enables the plate 11 to be drawn out as the ends of the cars move apart for the length of the coupling-link after being 25 coupled.

Having thus described my invention, what I claim, and desire to secure by Letters Patent, is—

1.. The combination of the rod pivotally

supported at its inner end and capable of vertical movement at its outer end, the angled plate 11, secured on the outer end of said rod, the horizontal levers 22, pivoted on the end of the car and having the slotted inner ends which engage the outer end of the rod 13, and 35 the vertical lever 23, having the curved lower end extending under the outer end of the rod 13, substantially as set forth.

2. The combination of the bearing-roll 17, pivoted at its ends and formed with the transverse opening, the rod 13, passing through said roll and through vertical slots in the cross-pieces 16, the spiral springs 18 20, arranged as specified, the angled plate 11, secured on the outer end of the rod 13, the horizontal levers 22, pivoted on the end of the car and having the slotted inner ends which engage the outer end of the rod 13, and the vertical lever 23, having the curved lower end extending under the outer end of the rod 13, substantially as set forth.

In testimony whereof I affix my signature in presence of two witnesses.

EDWARD A. MORROW.
